CLAIM

The ornamental design for a sunroof canopy for a golf car, as shown and described.

DESCRIPTION

FIG. 1 is a perspective view of a sunroof canopy for a golf car showing my new design;

FIG. 2 is an enlarged right side elevational view thereof, which is a mirror image of the left side not shown;

FIG. 3 is an enlarged front elevational view thereof;

FIG. 4 is an enlarged rear elevational view thereof;

FIG. 5 is an enlarged top plan view thereof; and,

FIG. 6 is an enlarged bottom plan view thereof.
